O. HARROD

FLUID FUEL BURNER

Filed Feb. 24, 1925

Inventor
Ora Harrod, by
Gross & Collings
Attorneys

UNITED STATES PATENT OFFICE.

ORA HARROD, OF LAWRENCEVILLE, ILLINOIS.

FLUID-FUEL BURNER.

Application filed February 24, 1925. Serial No. 11,217.

To all whom it may concern:

Be it known that I, ORA HARROD, a citizen of the United States, residing at Lawrenceville, in the county of Lawrence and State 5 of Illinois, have invented certain new and useful Improvements in Fluid-Fuel Burners, of which the following is a specification.

This invention relates to fluid fuel burners and has for one of its objects to provide 10 a device of this character which will be simple in construction, comparatively inexpensive to manufacture and more efficient in use than those that have been heretofore 15 proposed.

A further object of the invention is to provide a fluid fuel burner which is particularly adapted to handle heavy viscous oils which may contain a large amount of free 20 carbon or other suspended matter, such for example, as cracking plant residuums, etc.

A still further object of the invention is to provide a burner which will accomplish 25 a more perfect atomization of the oil and which will produce a short wide flame close to the burner tip whereby the deposit of soot or carbon on the brick work and flues of the furnace resulting from the impinging 30 of long flames which produce only incomplete combustion, will be eliminated.

With the above and other objects in view which will appear as the description proceeds, the invention consists in the novel details of construction and combinations and 35 arrangements of parts, more fully and hereinafter disclosed and particularly pointed out in the appended claims.

Referring to the accompanying drawing forming a part of this specification in which 40 like numerals designate like parts in all the views,

Fig. 1 is a top plan view of a burner constructed in accordance with the present invention; and,

Fig. 2 is a horizontal longitudinal sectional view through the burner shown in 45 Fig. 1.

Referring more particularly to the said drawings, the numeral 5 indicates the main body member of the burner which may conveniently take the form of a casting of substantially the shape shown. The said body is provided with two interior chambers, 6 and 7, which are connected by a 50 threaded passage 8, which receives one end of a pipe or tube 9 which projects through

the chamber 7 and for some distance beyond the end of the body member 5, as will be readily understood from the drawings. The said body member 5 is also provided at one 60 end with a threaded opening 11 of somewhat larger diameter than the tube or pipe 9 which opening receives the threaded end 12 of the enlarged outer tube or sleeve 13 which surrounds in spaced relation the tube 65 or pipe 9.

Within the tube 9, which constitutes the oil passage of the burner, there is mounted a screw or spiral 15 which is rotatable therein under the action of a propeller member 16 70 which is provided at the extreme end of the said spiral and beyond the ends of the tubes 9 and 13. The opposite end of the said spiral or screw is provided with a reduced shaft 17 which passes out of the left hand end of the body member 5, through a suitable gland or stuffing box 18 and carries a fly wheel 19. The said shaft 17 is grooved as indicated at 20 to receive the inwardly projecting end 21 of the thrust member 22 80 which is secured as by the screws 23 to the body member 5.

As above stated the outer sleeve 13 is mounted in spaced relation relative to the inner tube 9, thereby providing an annular 85 passage 25 which leads from the steam chamber 7 to the discharge end of the burner. Adjacent this said discharge end there is provided a plurality of inclined baffle members 26, (see Fig. 2) which not 90 only serve to retain the ends of the tubes in spaced relation but also to impart a whirling motion to the steam as it is discharged from the nozzle to impinge upon the blades 95 of the propelling device 16.

Oil or other suitable fuel may be supplied to the chamber 6 of the burner by means of a suitable supply pipe 30 and if desired, a continuation 31 of this pipe may lead from the other side of the body member 5 to 100 other similar burners or back to the source of supply, whereby a continuous circulation of the fluid fuel may be had. In like manner, steam may be supplied to the steam chamber 7 through a supply pipe 32 and a 105 continuation 33 of this pipe may lead from the other side of the body member 5 to additional burners.

The operation of the present burner will be clear from the foregoing, but it may be 110 briefly summarized as follows:

Oil and steam being supplied to the re-

spective chambers 6 and 7 from the supply pipes 30 and 32, the steam being under pressure will flow from the chamber 7 through the annular passage 25 between the sleeve 13 and the tube 9 past the inclined baffle members 26 and will be discharged with a swirling motion from the burner tip to impinge upon the blades of the propeller 16. The action of the steam so discharged upon the propeller will produce rotation of the latter with consequent rotation of the screw or spiral 15 which projecting into the oil chamber 6 will have the effect of positively feeding the oil therefrom through the tube 9 to the discharge end thereof, where it will meet the steam being discharged from the passage 25 and be commingled therewith. The walls of the tube 9 are preferably made as thin as practicable in order that a portion of the heat of the steam in the surrounding passage 25 may be transferred to the oil during its passage through the tube 9 whereby it is preheated, to the end that its atomization at the burner tip will be facilitated. As the said oil is discharged from the extreme end of the tube 9 it meets the swirling jet of steam issuing from the end of the passage 25 and this swirling action together with the cutting or chopping action of the blades of the propeller 16 will produce an extremely fine atomization of the oil and a thorough mixture thereof with the steam. Furthermore the action of the parts including the propeller 16 is such that when the commingled oil and steam are ignited a relatively short wide flame will result, producing substantially complete combustion close to the burner tip with the result that the deposit or carbon or soot which is common upon the brick work and flues of furnaces which employ burners producing long narrow flames with consequent incomplete combustion, will be eliminated.

While the primary function of the spiral or screw 15 is to feed the oil through the tube 9 it will also serve to keep the oil passage free of deposits of free carbon or other matters which may be suspended in the oil and which in the absence of the screw would tend to clog and completely close the said tube 9. The operation of the said screw is made considerably smoother by the provision of the fly wheel 19 at the end thereof, and the said wheel also serves to overcome any additional friction within the tube 9, should a carbon deposit start to form therein.

While one form of the invention has been illustrated and described, it is obvious that those skilled in the art may vary the details of construction as well as the precise arrangement of parts without departing from the spirit of the invention, and therefore, it is not wished to be limited to the above disclosure except as may be required by the claims.

What I claim is:

1. In a fluid fuel burner, a body member having fuel and steam chambers; a tube providing a fuel discharge passage communicating with said fuel chamber; a sleeve surrounding said tube in spaced relation, providing a steam discharge passage communicating with said steam chamber; rotatable mechanical means in said tube for forcing fuel therethrough; and means carried by said last named means adapted to be acted upon by the discharge of said steam to produce rotation of said forcing means said rotation producing means also serving to assist in the atomization and mixing of the fuel and steam.

2. In a fluid fuel burner, a body member having fuel and steam chambers; a tube providing a fuel discharge passage communicating with said fuel chamber; a sleeve surrounding said tube in spaced relation, providing an annular steam chamber; a screw rotatably mounted in said tube, extending into said fuel chamber; and a propeller carried by said screw, adapted to be acted upon by the discharge of said steam to produce rotation of said screw said propeller also serving to assist in the atomization of said fuel and steam.

3. In a fluid fuel burner, a body member having fuel and steam chambers; a tube providing a fuel discharge passage communicating with said fuel chamber; a sleeve surrounding said tube in spaced relation, providing an annular steam discharge passage communicating with said steam chamber; means in said steam passage for imparting a whirling motion to said steam as it is discharged; a screw rotatably mounted in said tube, extending into said fuel chamber; a propeller mounted on one end of said screw, adapted to be acted upon by the discharge of said steam to produce rotation of said screw; a fly wheel carried by said screw; and means carried by said body member for taking the end thrust of said screw.

In testimony whereof I affix my signature.
ORA HARROD.
